UNITED STATES PATENT OFFICE.

THOMAS MIRK, OF SAN FRANCISCO, CALIFORNIA.

GAGE-GLASS PROTECTOR.

SPECIFICATION forming part of Letters Patent No. 758,767, dated May 3, 1904.

Application filed August 19, 1903. Serial No. 169,967. (No model.)

To all whom it may concern:

Be it known that I, THOMAS MIRK, a citizen of the United States, residing in the city and county of San Francisco, State of California, have invented certain new and useful Improvements in Gage-Glass Protectors; and I do hereby declare the following to be a full, clear, and exact description of the same.

The present invention consists of a protector designed to wholly or partially cover a gage-glass, the object being to protect the gage-glass from being damaged and at the same time prevent the pieces of flying glass in case the glass should burst or break from any cause from injuring the eye of the person in charge thereof.

To comprehend the invention, reference should be had to the accompanying sheet of drawings, wherein—

20 Figure 1 is a view in elevation of a gage-glass with the improved protector applied thereto. Fig. 2 is a top plan view of the protector. Fig. 3 is an enlarged detail view, partly in section, of the drive-disk and its supporting-plate; and Fig. 4 is a detail broken sectional view of a portion of the drive-disk and supporting-plate.

The numeral 1 is used to indicate an ordinary gage-glass located between the fittings 2 3. This gage-glass is inclosed, preferably, by a horizontally-rotatable protector, which in the present case consists of spaced disks 4 5, connected circumferentially by a series of vertical wires 6. The disks are loosely mounted upon the extensions 7 7', so as to be free to revolve thereon. Disk 4 shall be termed the "drive-disk," inasmuch as it is acted upon by the upward suction or air-draft to rotate the protector. This disk has secured to its periphery a series of short projecting blades or vanes 8, which are set at an angle to the axis of the disk 4. For the purpose of creating a strong suction or air-current to act upon the vanes of the drive-disk there is arranged above the fitting 2 a funnel 9. This funnel creates a strong upward current of air, which entering the enlarged bottom thereof acts upon the vanes or blades 8 the same as a current of air against a windmill and causes 45 the same to rotate the disk 4 to drive the pro-

55 tector at a comparatively high rate of speed. To reduce friction between the disk 4 and its fixed supporting-plate 4', there is interposed between the said disk and supporting-plate the ball-bearings 10.

The utilization of the blades or vanes 8 for imparting rotation to the disk 4 is preferred, although any suitable means may be employed for this purpose. A simple manner of arranging the disk 4 to utilize the force of the 60 upwardly-drawn air consists in forming a series of tangential openings 11 circumferentially of the disk and supporting-plate 4', near the periphery thereof. As the air is drawn through these openings the effect will be to 65 impart rotation to the disk for the driving of the protector. Preferably these tangential openings are used in addition to the blades or vanes 8.

70 Inasmuch as the protector rotates at a comparatively high speed, the fine vertical wires 6 become substantially invisible, similar to the spokes of a driven wheel. Hence there is no interference as to the seeing or examining of the gage-glass. In case of breakage, however, of the gage-glass, due to high pressure, sudden expansion or contraction, or other causes, the wires 6 will confine the flying pieces of glass and prevent the same injuring the person attending the gage. 75

80 It is obvious that the gage-protector may be constructed of any suitable material and the form thereof varied without departing from the invention, the essential feature of which resides in a rotatable protector arranged 85 to wholly or partially cover a gage-glass.

Having thus described the invention, what is claimed as new, and desired to be protected by Letters Patent, is—

1. The combination with a water-gage, of an 90 open protector covering the same, and means for imparting continuous rotation to the protector.

2. The combination with a water-gage, of a 95 cylindrical open protector enveloping the same, and means for imparting continuous rotation to the protector.

3. A water-gage protector, the same comprising an upper and lower disk, a series of spaced rods or wires connecting the same cir- 100

cumferentially, and means for imparting rotation to the protector.

4. The combination with a water-gage, of a protector rotatably connected therewith, the same comprising an upper and lower disk, a series of spaced rods or wires connecting the same circumferentially, and means for causing the protector to rotate freely around the gage by an upward current of air.
- 10 5. The combination with a water-gage, of a protector rotatably connected therewith, the same comprising an upper and lower disk, a

fixed supporting-plate for one of the disks, a series of spaced wires circumferentially connecting the disks, ball-bearings interposed between the fixed plate and the disk supported thereby, and means for imparting rotation to the protector.

In witness whereof I have hereunto set my hand.

THOMAS MIRK.
